UNITED STATES PATENT OFFICE.

THOMAS FOLLEN, OF LA FAYETTE, INDIANA.

DESIGN FOR A TIRE.

55,600.

Specification for Design.

Patented July 6, 1920.

Application filed March 18, 1920. Serial No. 366,995. Term of patent 14 years.

To all whom it may concern:

Be it known that I, THOMAS FOLLEN, a citizen of the United States, residing at La Fayette, in the county of Tippecanoe and State of Indiana, have invented a new, original, and ornamental Design for Tires, of which the following is a specification, reference being had to the accompanying drawing, forming part thereof.

Figure 1 is a plan view; and

Fig. 2 is a section of an automobile tire showing my new design.

I claim:

The ornamental design for a tire, as shown.

THOMAS FOLLEN.
